UNITED STATES PATENT OFFICE

CARL A. MATSON, OF LYNNFIELD, MASSACHUSETTS, ASSIGNOR TO SHOE LACE COMPANY, LTD., OF PROVIDENCE, RHODE ISLAND, A CORPORATION OF RHODE ISLAND

BANDING MACHINE

Application filed January 11, 1927. Serial No. 160,499.

This invention relates to an improved banding machine and is herein shown as embodied in a machine for automatically applying an enclosing band or label to an article or bundle of articles.

Considerable difficulty has been encountered in the past in insuring effective operation of automatic wrapping or labeling machines on account of faulty adhesion of the bands or labels and on account of irregularity in the supplying of the labels to the label applying or wrapping mechanism.

It is, accordingly, an object of the invention to provide improved mechanism for applying bands or labels, to articles or bundles of articles, such for example as pairs of shoe laces, and in accordance with one feature of the invention the illustrated banding machine is constructed and arranged to fold a label about a bundle and fasten it securely by the application of pressure and heat simultaneously to the folded ends of the label one of which is coated with a gum of such a nature that it is rendered tacky when heated. To this end, the folding means of the illustrated machine comprises a jaw containing a heating unit toward which the bundle to be banded is positively forced and against which the gummed end of the label is pressed, thereby insuring the adhesion of the gummed end of the label to the other end thereof.

In accordance with another feature of the invention, the illustrated banding machine is provided with an improved label magazine for supplying labels one by one to the folding means which magazine is constructed and arranged to maintain a supply of labels at its delivery end, the stack of labels being fed to bring another label to the end of the magazine when ever the endmost label is removed. When the magazine is brought into engagement with the wrapping mechanism it is held resiliently in juxtaposition to a vacuum plate which is adapted to retain thereon the endmost label in the magazine as it is retracted from the wrapping device.

In another aspect the invention includes an oscillating bundle support arranged intermittently to move a bundle or article to be banded into engagement with the label on the

vacuum plate which is yieldingly received in a recess in the support for the banding device. In order partially to encircle the bundle with the label, the bundle support is moved to carry the bundle within the above-mentioned recess, causing the label to be folded about three sides of the bundle. At the completion of the wrapping operation as above described the bundle support is operated to withdraw the banded bundle from the recess in the wrapping device. The bundle support may be loaded and discharged manually and is constructed and arranged to be operated in timed relation with the label magazine and folding or wrapping mechanism.

In the accompanying drawings illustrating an embodiment of my invention,

Fig. 1 is a side elevation, partly in section, of a banding machine embodying my invention;

Fig. 2 is an end elevation;

Fig. 3 is a sectional plan view on the line III-III of Fig. 1;

Fig. 4 is a sectional side elevation on the line IV-IV of Fig. 2, and

Fig. 5 is a vertical, sectional elevation on the line V-V of Fig. 4 with a folding jaw and bundled article removed.

Referring to the drawings, 10 designates a base or platform on which is mounted in any suitable manner a hollow frame 11, in the side members of which are alined bearings 12 (Fig. 2) rotatably supporting a shaft 13. The shaft 13 is provided at one end with tight and loose pulleys 14 and 15 respectively, over which runs a belt 16 for transmitting power to the shaft 13 from any suitable source. Formed on the lower front edge of the frame 11 are spaced guideways 17 (Fig. 1) in which is mounted for vertical reciprocation a slide member 18, which member is provided with a dove-tailed slide 19 (Fig. 3) engaging in the slideways 17. Formed on the face of the member 18 opposite the face containing the slide 19 is a guideway 20, in which is mounted a dove-tailed slide 21. Secured to the front face of the slide 21 is a hollow open-ended casing 22 provided on its open front side with an enclosing cover 23. Slidably mounted in the casing 22 is a base

65

70

pivot screw 65 in a counterclockwise direction as viewed in Fig. 1. Formed on the top end of the lever 70 is a cam surface 730.

Rotatably mounted in suitable bearings in the upper forward end of the frame 11 is a shaft 74 and secured to such shaft and extending downwardly therefrom is a cam plate 75 which is adapted on rocking movement of the shaft 74 to engage with the upper end of the rod 52. Also secured to the shaft 74 and extending downwardly therefrom is a cam arm 76 which is adapted on rocking movement of the shaft 74, in one direction to engage the pin 69 on the lever 66 and, in the other direction, to engage the cam surface 730 on the lever 70, thus oscillating alternately the lever 66 and the lever 70. Secured to the shaft 74 and extending rearwardly therefrom within the casing 11 is a lever 77 and to the inner end of this lever is pivotally attached the upper end of a cam rod 78. This cam rod 78 passes through a bearing member 79 in the casing 11 and has rotatably mounted at its lower end a cam follower 80 which engages with a cam 81 secured to the shaft 13.

In the operation of the machine the magazine casing 22 is first filled with gummed labels 30 and heat is supplied to the heating element 72 from any suitable source. The belt 16, assumed to be in motion, is moved from the loose pulley 15 over onto the tight pulley 14, thereby rotating the shaft 13 in the direction of the arrow shown in Fig. 1. The air pump above referred to is put into operation to draw air through the perforated plate 62, recess 53 and pipe 54 thereby creating a partial vacuum in the recess when the perforations in the plate are covered. The shaft 13 in its rotative movement will position the cam 43 so that the spring 38 will be able to rotate the lever 36 about the shaft 37 and will thus move the magazine casing 22 upwardly and will bring the endmost gummed label in engagement with the perforated plate 62. The partial vacuum produced within the plate 62 causes the endmost label in the magazine to be retained on the plate as continued rotation of the shaft 13 forces the magazine casing downward and into the position shown in Fig. 1. The operator, standing in front of the machine, or to the left as viewed in Fig. 1, next inserts the article or bundle of articles to be wrapped between the pairs of holding jaws 45 and 46, which at this time are below the plate 62, and the continued rotation of the shaft 13 will cause the cam 49 to engage with the cam roller 48 and the pairs of jaws 45 and 46 will be moved upwardly, moving the article or bundle of articles upwardly into engagement with the label 30 (Fig. 4) held on the bottom of the perforated plate 62. Continued upward movement of the jaws 45 and 46 will carry the bundle into the transverse recess 51, compressing the springs 60 and caus-

ing the label to be folded about three sides of the bundle, and as the shaft 13 continues its rotation, the cam 81 will cause an oscillating movement of the shaft 74, first in a clockwise direction as viewed in Fig. 1, whereupon the cam arm 76 will engage with the pin 69 on the lever 66 and the transverse jaw member 68 carried thereby will engage with a free ungummed end of the label 30 and move the same across the lower face of the article or bundle of articles. Upon the opposite movement of the shaft 74, the arms 75 and 76 will rotate to the right as shown in Fig. 1, whereupon the arm 75 will engage the rod 52 and the arm 76 will engage the cam face 730 of the arm 70.

Upon further rotation of the shaft 74, the cam 76 operates the lever 70 to fold the remaining loose end of the label about the bundle. Simultaneously, the cam 75 cooperating with the rod 52 forces the bundle toward the heating element 72, which forms a cross-plate on the lever 70, thus squeezing the bundle and compressing the folded ends of the label to cause them to adhere together when the heat of the heating element 72 renders the gum on the label tacky. The labels employed having as an adhesive one that is rendered tacky when heated, their ends may be brought instantaneously into adhesive engagement. Even in a tacky condition such an adhesive is a relatively strong binder, and since there is but little danger of the ends of the label coming apart the speed of the machine is limited only by the ability of the operator to feed the article or bundles of articles 85 to the pairs of jaws 45 and 46. The continued rotation of the shaft 74 causes the cam arms 75 and 76 to be moved out of engagement with the pin 52 and cam surface 730 respectively and also the jaws or arms 45 and 46 will be moved downwardly, whereupon the operator now removes the banded article or bundle of articles from the machine and inserts an unbanded bundle in such jaws. This sequence of operations may be repeated indefinitely.

While I have necessarily shown and described the illustrated embodiment of my invention somewhat in detail, it is to be understood that I may vary the size, shape and arrangement of parts comprising my device within reasonably wide limits without departing from the spirit of the invention.

Having thus described my invention, what I claim as new is:

1. In a bundle banding machine, in combination, a label retaining plate, a label magazine, means for moving said magazine yieldingly into juxtaposition to and away from said plate to deliver a label thereto, work holding means constructed and arranged to carry a bundle into engagement with the label on said plate,

- and means for wrapping the ends of said label about said bundle.
2. In an improved banding machine, the combination of a yieldingly mounted plate, means for associating a gummed label therewith, a pair of sets of material holding jaws associated with said plate, means for moving said jaws upward with respect to said yieldingly mounted plate, and means associated with said plate for folding the gummed label.
3. In an improved banding machine, the combination of a yieldingly mounted plate, means for associating a gummed label therewith, a pair of sets of material holding jaws associated with said plate, means for moving said jaws upward with respect to said yieldingly mounted plate, whereby said label partially encircles the material to be banded and with its free ends extending downwardly and means for folding said free ends over against the material to be banded and over each other.
4. In an improved banding machine, the combination of a yieldingly mounted plate, means for associating a gummed label therewith, a pair of sets of material holding jaws associated with said plate, means for moving said jaws upward with respect to said yieldingly mounted plate, whereby said label partially encircles the material to be banded and with its free ends extending downwardly, means for folding said free ends over against the material to be banded and over each other, and means for applying heat to the free ends of the label, whereby the same are caused to adhere together.
5. In an improved banding machine, the combination of a yieldingly mounted plate, means for associating a gummed label therewith, a pair of sets of material holding jaws associated with said plate, means for moving said jaws upward with respect to said yieldingly mounted plate, whereby said label partially encircles the material to be banded and with its free ends extending downwardly, means for folding said free ends over against the material to be banded and over each other, and means for applying heat and pressure to the free ends of the label, whereby the same are caused to adhere together.
6. In an improved banding machine, the combination of a yieldingly mounted plate, means for associating a gummed label therewith, a pair of sets of material holding jaws associated with said plate, means for moving said jaws upward with respect to said yieldingly mounted plate, whereby said label partially encircles the material to be banded and with its free ends extending downwardly, means for folding said free ends over against the material to be banded and over each other, and means for simultaneously applying heat and pressure to the free ends of the label, whereby the same are caused to adhere together.
7. In a bundle banding machine the combination of a yieldingly mounted plate, means for supplying a gummed label thereto, oscillating bundle holding means for moving the bundle into and out of juxtaposition to said plate, and means associated with said plate for folding the gummed label about the bundle when held in juxtaposition to said plate.
8. In a bundle banding machine, in combination, a label magazine, a yieldingly mounted plate, means for moving said magazine into and out of juxtaposition to said plate, means for retaining on said plate as the magazine is moved therefrom the endmost label therein, oscillating work holding means constructed and arranged to move a bundle into and out of juxtaposition to said plate, and means for wrapping said label about said bundle when in juxtaposition to said plate constructed and arranged to be operated in timed relation with the motion of said magazine and work holding means.
9. In a bundle banding machine, in combination, a yieldingly mounted plate constructed and arranged to retain thereon a label having a gummed margin, means for holding a bundle against the label on said plate, opposed pivoted wrapping jaws constructed and arranged successively to fold the loose ends of the label about the bundle held against the label, and means for positively forcing the bundle against one of said jaws as it wraps the gummed end of the label about the bundle to insure the adhesion of the gummed end of the label to the other end thereof.
10. In a bundle banding machine, in combination, a yielding label retaining plate, a label magazine, means for moving said magazine yieldingly into juxtaposition to said label retaining plate to deliver a label thereto, work holding means constructed and arranged to carry a bundle into engagement with a label on said plate, and means for wrapping the ends of said label about said bundle.
11. In a bundle banding machine, in combination, a label retaining plate, a magazine for holding a pile of labels, means for holding the endmost label of the pile substantially in the plane of the delivery end of the magazine, means for moving said magazine to bring its delivery end into juxtaposition to said plate to deliver a label thereto, work holding means constructed and arranged to carry a bundle into engagement with a label carried by said plate, and means for wrapping the ends of said label about said bundle.
12. In a bundle banding machine, in combination, a label retaining plate, a label magazine, means for forcing labels therein to

- ward its delivery end, means to prevent extrusion of the labels from the magazine by said first-mentioned means, work means for moving the magazine to bring its delivery end into juxtaposition to said plate to deliver a label thereto, holding means constructed and arranged to carry a bundle into and out of engagement with the label carried by said plate, and means for wrapping the ends of said label about said bundle when it is in contact with said label. 10
13. In a bundle banding machine, in combination, a label retaining plate, a label magazine, gravitationally operated means for forcing labels in the magazine toward the delivery end thereof, means to prevent extrusion of the labels from the magazine by said first-mentioned means, means for moving said magazine into juxtaposition to said plate to deliver a label thereto, work holding means constructed and arranged to carry a bundle into engagement with a label held on said plate, and means for wrapping the ends of said label about said bundle. 15
14. In a bundle banding machine, in combination, a yieldingly mounted plate adapted to retain a label thereon, a label magazine constructed and arranged to be resiliently held in juxtaposition to said plate, yielding means for urging the labels in the magazine toward the delivery end of the magazine thereof, work holding means constructed and arranged to carry a bundle into engagement with a label held by said plate, and means for wrapping the ends of said label about said bundle. 20
15. In a bundle banding machine, in combination, a yieldingly mounted plate adapted to retain a label thereon, a magazine constructed to hold a pile of labels, means within the magazine for holding the endmost label in the pile substantially in the plane of the delivery end of the magazine, a reciprocable slide supporting the magazine, and means for operating said slide to bring the magazine into association with the label retaining plate to deliver a label thereto. 25
16. In a bundle banding machine, a yieldingly mounted plate adapted to retain a label thereon, a magazine for holding a pile of labels, means within the magazine for holding the endmost label in the pile substantially in the plane of the delivery end of the magazine, a reciprocable slide supporting the magazine, means for operating said slide whereby the magazine may be brought into juxtaposition to the label retaining plate, and resilient connections between the magazine and slide whereby the magazine and plate are brought yieldingly together. 30
17. In a bundle banding machine, the combination of a plate mounted yieldingly to slide within a recess, means for supplying a gummed label thereto, oscillating bundle holding jaws for carrying a bundle in con- 35
- tact with the label on said plate into said recess whereby said bundle is partially encircled by the label the ends of which extend away from said plate, and means for folding said ends about the bundle and one end over the other. 70
18. In a bundle banding machine, the combination of a yieldingly mounted label retaining plate, means for supplying a gummed label thereto, oscillating bundle holding jaws for moving a bundle into contact with the label on said plate causing said plate to yield whereby said label partially encircles the bundle to be banded and its ends extend away from said plate, means for folding said ends about the bundle and one end over the other, and means for applying heat to the gummed end of the label thereby causing the ends to adhere together. 75
19. In a bundle banding machine, the combination of a yieldingly mounted label retaining plate, means for supplying a gummed label thereto, bundle holding means constructed and arranged to hold a bundle against the label on said plate, means for folding the ends of the label about the bundle to be banded and one end over the other, and means for applying heat and pressure to the folded ends of the label thereby causing them to adhere together. 80
20. In a bundle banding machine, the combination of a label retaining plate mounted yieldingly to slide within a recess, means for supplying a gummed label thereto, bundle holding means constructed and arranged to carry a bundle into said recess whereby said label is caused partially to encircle the bundle to be banded and its ends extend away from said plate, means for folding said ends about the bundle and one end over the other, and means for simultaneously applying heat and pressure to the folded ends of the label thereby causing them to adhere together. 85
21. In a bundle banding machine, the combination of a yieldingly mounted label retaining plate, means for supplying a gummed label thereto, bundle holding means constructed and arranged to move a bundle into and out of juxtaposition to said plate, means for wrapping the bundle when in engagement with a label on said plate comprising jaws successively oscillating beneath the bundle to wrap the ends of the label about it, and means for squeezing the bundle as the wrapping of the label about the bundle is completed to insure the adhesion of the gummed end of the label to its other end. 90
22. In a bundling and banding machine, bundle holding means, means for folding a label having a gummed end into a wrapper about a bundle on said holding means, and means for applying heat and pressure to the folded ends of the wrapper thereby to insure their adhesion. 100
23. In a bundling and banding machine, 105
- 110
- 115

- 130

bundle holding means, jaws for folding a label having a gummed end into a wrapper about a bundle on said holding means, means for heating one of said jaws, and means for urging said bundle toward said heated jaw thereby to compress the folded ends of the wrapper insuring their adhesion.

24. In a bundling and banding machine, the combination of a label retaining plate, means for supplying a gummed label thereto, bundle holding means, means for bringing a label on said plate and a bundle on said holding means into contact, means for folding the ends of said label about the bundle and the gummed end over the other, and means for applying heat to the gummed end of the label thereby fusing the gum thereon and causing the ends to adhere together.

25. In a bundling and banding machine, the combination of a label retaining plate, means for supplying a gummed label thereto, bundle holding means, means for bringing a label on said plate and a bundle on said holding means into contact, means for folding the ends of said label about the bundle and the gummed end over the other, and means for simultaneously applying heat and pressure to the folded ends of the label insuring their adhesion.

30 26. In a bundling and banding machine, in combination, a label retaining plate, means for supplying a gummed label thereto, bundle holding means, means for bringing a label on said plate and a bundle on said holding means into contact, jaws for folding the ends of said label about the bundle, means for alternately operating said jaws to fold the gummed end of the label over the other, and means for heating one of said jaws whereby the gum on the label is fused insuring the adhesion of its ends.

27. In a bundling and banding machine, in combination, a resiliently yielding label retaining plate, means for supplying a gummed label thereto, bundle holding means, means for bringing a bundle on said holding means and a label on said plate into contact causing said plate to yield, means for folding the ends of the label about the bundle and the gummed end over the other, said folding means being arranged to resist the pressure of said plate against the bundle thereby compressing the folded ends of the label, and means for heating the gummed end of the label to fuse the gum thereon insuring its adhesion to the other end.

28. In a bundling and banding machine, the combination of a label retaining plate mounted yieldingly to slide within a recess, means for supplying a gummed label thereto, bundle holding means, means for moving said plate and bundle holding means relatively to each other to carry a bundle against a label on said plate into said recess whereby said label is caused partially to encircle a

bundle to be banded, means for folding the ends of said label about the bundle and one end over the other, and means for applying heat and pressure to the folded ends of the label thereby causing them to adhere together.

In testimony whereof, I have signed my name to this specification.

CARL A. MATSON.
